UNITED STATES PATENT OFFICE.

RICHARD H. WESTERFIELD, OF KENTON, OHIO.

DESIGN FOR A RANGE.

SPECIFICATION forming part of Design No. 35,990, dated August 5, 1902.

Application filed June 6, 1902. Serial No. 110,558. Term of patent 3½ years.

To all whom it may concern:

Be it known that I, RICHARD H. WESTERFIELD, a citizen of the United States, residing at Kenton, in the county of Hardin and State of Ohio, have invented and produced a new, original, and ornamental Design for Ranges, of which the following is a specification, reference being had to the accompanying drawing, forming part thereof.

10 The figure is a perspective view of a range, showing my new design.

As shown in the drawing, the leading or material feature of my design consists in the ornamented side support 1, including two legs 15 and situated below the ornamented door 2.

Said door has an oval figure 3 near its center held in the arms of a cradle-like figure 4 and surmounted by a conventional bouquet 5.

Having described my invention, what I claim as new, and desire to secure by Letters 20 Patent, is—

The ornamental design for a range, as herein shown and described.

In testimony whereof I have signed my name to this specification in the presence of 25 two subscribing witnesses.

RICHARD H. WESTERFIELD.

Witnesses:

GERTRUDE RUBINS,
M. WACHALD.
